CLAIM

The ornamental design for a key organizer as shown and described.

DESCRIPTION

FIG. 1 is a top perspective view of a key organizer of my design.

FIG. 2 is a bottom perspective view of the key organizer of FIG. 1.

FIG. 3 is a side view of the key organizer of FIG. 1.

FIG. 4 is another side view of the key organizer of FIG. 1.

FIG. 5 is a top view of the key organizer of FIG. 1.

FIG. 6 is a bottom view of the key organizer of FIG. 1.

FIG. 7 is a front view of the key organizer of FIG. 1; and, FIG. 8 is a rear view of the key organizer of FIG. 1.

The broken lines shown in the figures are included for the purposes of illustrating portions of the environmental structure and form no part of the claimed design. Randomly dashed lines represent surface shading.

1 Claim, 5 Drawing Sheets
